W. K. HOWE

TRAIN CONTROL

Filed Sept. 6, 1924

UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK.

TRAIN CONTROL.

Application filed September 6, 1924. Serial No. 736,366.

This invention relates to automatic train control systems, and more specifically to switch protection means for a train control system of the continuous inductive type.

- 5 In the usual continuous inductive train control system, the brakes of a train are applied or the train speed is in some other way restricted by the lack of control current which flows in a trackway circuit in the usual 10 insulated blocks of the track rails under clear traffic conditions, and which is cut off by suitable means under dangerous traffic conditions ahead. In the usual railway system, points are encountered along the track- 15 way at which a spur track, branch line or siding leaves the main line trackway by means of a track switch, and these track switches when set for a turn-out move, constitute a dangerous hazard to approaching traffic. It 20 is evident that an open track switch in a given block of the trackway constitutes a hazard for approaching trains only, and that a train receding from the track switch need not be under restrictive control.
- 25 In view of the above and other considerations, it is proposed in accordance with the present invention to provide means operated in accordance with the position of a track switch, and acting to cut off the trackway 30 control current in the portion of an insulated block in the rear of the switch while allowing the control current to flow in the trackway circuit between the track switch and the exit end of the block when the switch is set 35 for a turn-out move. Other objects and advantages of the present invention will become apparent or will be pointed out as the description progresses.

In the drawings, a section of trackway 40 including a track switch and the protective control means embodying the present invention has been shown, together with a simplified and diagrammatic representation of the car-carried apparatus comprising a typical 45 train control system.

Referring particularly to the trackway apparatus, the track rails 1 are divided into blocks in the usual way by the insulating joints 2, the block I and the ends of the two 50 adjacent blocks H and J having been shown. As the trackway equipment in the adjacent blocks is assumed to be identical, the description of such equipment in one block only will be given, corresponding elements in the adjacent blocks being referred to by like refer-

ence characters having distinctive exponents.

Train control current is applied to the two track rails in series at each block from the transformer 3 whose primary winding is connected across the transmission line 4 as 60 shown. The secondary winding of the transformer 3 is connected to the track rails through the front contacts of fingers 5¹ and 6¹ of the track relay 7¹ and the transformer 8 as clearly shown. The track relay 7 is of 65 the type well known in railway signaling practice, and in the embodiment shown, is preferably of the direct current type and is connected across the track rails at the entrance end of the block. A track battery 9 70 is connected across the track rails at the exit end of each block in series with the secondary winding of the transformer 8 as shown. It is evident that the track relay 7 will be maintained energized by direct current from 75 the battery 9 flowing in the track rails when no train is present in the block under consideration, and that when a train enters such block, this current will be shunted from the track relay by the wheels and axles of 80 the train, causing the de-energization of this track relay and so cutting off the control current from the next block in the rear.

Wayside signals of the color light signal, 85 semaphore or any other suitable type may be employed in connection with the track circuits shown. These wayside signals may be operated from the track relay 7 in the manner well known in train control practice. For the purpose of illustration semaphore signals 90 Z have been conventionally represented at the entrance end of each block.

Referring now more particularly to the track switch protection means which constitutes the present invention, a typical track 95 switch S has been shown in the block I. As track switches and their operating means are well known to those skilled in the art of railway and signal practice, and as the particular switch construction and operating 100 means used forms no part of the present invention, the track switch S has been shown in a diagrammatic manner only, and it is assumed that suitable manual or automatic operating means are provided. A switch 105 box SW is provided adjacent the track switch and is operated by the operating rod 10 which moves in accordance with the position of the track switch as clearly shown. This operating rod 10 is pivotally connected 110

to the switch box contact fingers 11 and 12 which fingers are movably supported on a suitable insulating base in the switch box. At a point in the trackway just in advance 5 of the track switch S the track rails 1 are separated by the insulating joints 13. The switch box contact fingers 11 and 12 are connected to the track rails on either side of the insulating joints 13 in such a manner 10 that when the track switch S is set for train travel on the main line trackway the insulating joints 13 will be bridged by these contact fingers, and that when the track switch S is set in a position for a turn-out 15 move to the branch line or siding the track rails are divided by the insulating joints 13. It will also be noted that when the track switch S is set for a turn-out move the two track rails 1 in that section of the block 20 preceding the track switch S will be connected by a circuit including the wire 14 which is connected between two stationary contacts of the switch box contact fingers 11 and 12. This connection between the rails 25 in the entrance portion of the block prevents the leakage of control current from the exit portion of the block past the insulating joints 13 when the track switch is set for a turn-out move.

30 A railway vehicle has been conventionally represented in the block I by the wheels and axles 15, its normal direction of travel being indicated by the arrow. It should be understood that the railway vehicle may use any 35 suitable type of car-carried train control apparatus for restricting the train speed in accordance with control influences received from the trackway. In the specific embodiment shown for the purpose of illustration, a 40 type of car-carried control apparatus has been illustrated which acts to apply the brakes of a train or to initiate a restrictive brake application when a section of trackway is traversed in which no control current is present. The simplified car-control 45 apparatus as shown in the drawings employs two receiving coils 16, mounted in front of the leading axles of the vehicle, over and in inductive relation with the track rails. 50 These receiving coils are connected through a circuit which is resonated by the condenser T to an amplifier which has been conventionally represented at A. This amplifier 55 is preferably of the type which employs the usual vacuum tube circuits and which acts to respond to weak current impulses and to produce stronger current impulses in its output circuit. The output circuit 60 of the amplifier A is connected to the winding of the main relay MR as shown. This main relay is provided with a movable contact finger 17, which acts when closed to 65 complete a circuit to the brake control apparatus BA. The brake control apparatus,

which has been conventionally represented at BA, may be of any type which is suitable for train control practice, for instance it may cause an immediate brake application upon the de-energization of a circuit through 70 its windings, or such de-energization of its windings may initiate suitable mechanism which will set up more restrictive speed limits as the train progresses in dangerous territory. 75

With clear traffic conditions ahead, that is, with no train or other dangerous traffic condition in a given block, or in the next block in advance, it is evident that control currents flow in series in the track rails and 80 induce currents in the receiving coils 16 of a vehicle in the given block, so maintaining the main relay MR energized and preventing a restrictive brake application by the energization of the brake control apparatus BA 85 through the contact finger 17 to the main relay MR as clearly shown in the drawings. If, however, the control current is not flowing in the track rails of the given block 90 because of a train in that block shunting the track rails, or by reason of the de-energization of the track relay in the next block in advance due to a train or other dangerous traffic conditions in such advance block, the receiving coils 16 do not receive current, the 95 main relay MR is de-energized and the contact finger 17 of the main relay is retracted, causing the de-energization of the brake control apparatus BA and a subsequent 100 restrictive brake application. 105

Now assume that a train, equipped with the typical brake control apparatus described, enters the block I in which the track switch S and its protective apparatus is located, and that the track switch S is set in a position for train travel along the main line trackway. Assuming also that clear traffic conditions exist in the block J, train control currents are impressed upon the track rails in series at the entrance end of the block, pass through the track rails to the insulating joints 13 at the track switch S, and are there conducted past the insulating joints 13 by means of the switch box contact fingers 11 and 12 through circuits which are 110 obvious from the drawings, and pass through the wheels and axles of the train entering the block I. The train may thus proceed without restriction as in any other clear block when the track switch is set for 115 the main line trackway travel. 120

Now assume that the track switch S is open or set for a turn-out move, and that the train under consideration enters the block I. With the track switch in this position, the switch box contact fingers 11 and 12 are in the positions indicated by the dotted lines, the insulating joints 13 are no longer bridged and the track rails in that 125 portion of the block preceding the track 130

switch S are electrically connected through the wire 14 and a circuit which is obvious from the drawings. The receiving coils 16 of the train entering the block I fail to receive control currents from the track rails under this condition and the main relay MR of the car-carried apparatus is de-energized retracting its contact finger 17, de-energizing the brake control apparatus BA and causing a restrictive brake application. It is clear that by the use of the switch protecting apparatus just described a train is prevented from running into the switch set for a turn-out move, at an excessive speed, as far as possible.

It should be noted that when the track switch S is thrown to the position for a turn-out move to the branch line or siding, that the train control current is in no way interrupted in that section of the block I which lies between the track switch S and the exit end of the block. For this reason a train traveling in this exit portion of the block I does not undergo a restrictive brake application when the track switch S is thrown to a position for a turn-out move behind such train. This arrangement avoids unnecessary delays in traffic when the track switch is thrown with a train in the exit portion of the block.

It is to be understood in connection with the car-carried control apparatus that means are preferably provided to place this control apparatus in an inactive condition when the train enters into a branch line or other section of trackway which is not equipped for automatic train control. It is to be further understood that when the main relay MR is de-energized due to the lack of control current flowing in the track rails, the train may still proceed at some minimum speed say, 15 miles an hour, until the control current returns in the track rails so that a train may proceed over the switch S at a low speed.

As the switch protection apparatus which comprises the present invention has been described in connection with a rather specific form of train control system, it should be clearly understood that the application of this switch protection means is not limited to the type of control system shown, and that many additions, modifications and changes could be made in the system shown without departing from the spirit of the present invention. For instance, two sets of receiving coils on the vehicle might be used, responding to two control currents in the track rails; means for reversing the connections to the receiving coils by an automatically or manually operable switch might be shown; or many other changes and combinations might be made.

What it is desired to secure by Letters 65 Patent is:

1. A trackway circuit for an automatic train control system comprising a section of track rails containing a track switch and divided into two portions by insulating joints at said track switch, a source of electrical energy connected across the track rails of one of said portions, a track relay connected across the rails of the other of said portions, and means controlled by the position of said track switch for electrically connecting the rails of said portion having a track relay when the switch is in one position, and for transmitting said electrical energy across said insulating joints when said track switch is in the other position. 80

2. In an automatic train control system, a section of track rails divided into an entrance portion and an exit portion by insulating joints, a track switch adjacent said joints, means for supplying a control current 85 to said exit portion and means controlled by the position of said track switch for electrically connecting said two portions when said track switch is in one position and for breaking said connection and connecting 90 the rails of the entrance portion when said track switch is in the other position.

3. In an automatic train control system, the combination with car-carried apparatus for applying the brakes of a vehicle upon 95 the cessation of control influences normally received from the trackway, a section of track rails containing a track switch leading to a branch trackway, said section being divided into an entrance portion and an exit 100 portion by insulating joints adjacent said track switch, means for supplying the current for producing said control influences to said exit portion under favorable traffic conditions ahead, and means actuated by the 105 movement of said track switch for bridging said insulating joints and so transmitting said current to the entire section when said track switch is set for vehicle travel along said section, and for disconnecting said portions and electrically connecting the rails of said entrance portion when said track switch is set for vehicle travel on said branch trackway, whereby a brake application will 110 be effected on a vehicle in said entrance 115 portion when said track switch is set for vehicle travel on said branch trackway.

4. The combination with a main railway track divided into blocks by insulating joints, a source of alternating current for train control purposes connected across the track rails at the exit end of each block, a track switch leading to a diverging trackway located at an intermediate point in a block between two successive signals, insulating joints in the main track at said track switch, and means for bridging said insulating joints only when said track switch is set for train travel along the main track. 120 125

5. In combination with a railway track 130

divided into blocks by insulating joints, a track relay connected across the rails at the entrance end of each block, a source of signaling current connected across the track rails at the exit end of each block, a track switch at an intermediate point in a block leading to a diverging trackway, an insulating joint in each track rail adjacent said track switch and a circuit controller mechanically connected to and operated by said track switch acting to bridge each of said last mentioned insulating joints when said track switch is set for train travel along the main track but which leaves said last mentioned insulating joints unbridged when said track switch is set for train travel over said diverging trackway.

6. Trackway apparatus for train control purposes for train control systems of the continuous inductive type in which a train is permitted to proceed in response to train control current flowing in the two track rails in series and detected on the train comprising

ing, a track divided into blocks by insulating joints; a track relay at the entrance end of each block, a source of signalling current connected across the track rails at the exit end of each block, a source of train control current connected in series with said source of signalling current, a track switch leading to a diverging trackway located at an intermediate point in a block, and means for interrupting the electrical continuity of the track rails at said intermediate point when said track switch is set for train travel over said diverging trackway, whereby the track relay at the entrance end of said block is de-energized and no train control current can be detected in the rear of said track switch, whereas train control current can be detected by a train traveling in said block ahead of said track switch when said switch is set for train travel over said diverging trackway.

In testimony whereof I affix my signature.
WINTHROP K. HOWE.
